James F. Duhamel,
ATTORNEY.

UNITED STATES PATENT OFFICE.

WILLIAM A. HENDERSON, OF LARCHMONT, NEW YORK, ASSIGNOR TO HOLBROOK COMPANY, OF NEW YORK, N. Y., A CORPORATION OF NEW YORK.

HINGE-LOCK.

1,248,854.

Specification of Letters Patent.

Patented Dec. 4, 1917.

Application filed February 20, 1917. Serial No. 149,764.

To all whom it may concern:

Be it known that I, WILLIAM A. HENDERSON, a citizen of the United States, and resident of Larchmont, in the county of 5 Westchester and State of New York, have invented certain new and useful Improvements in Hinge-Locks, of which the following is a specification.

This invention relates to locking hinges 10 and is especially adapted for use where articles are to be folded or collapsed, the object of the invention being to hinge two parts of a frame or other structure together and to provide a latch to be operated by a 15 screw and acting on an inclined surface to firmly unite and brace the two parts together or to quickly release them, the parts being so let into the woodwork of the structure as to be almost invisible and precludes 20 the chances of hooking and catching articles of clothing while in its various positions.

These and other objects and details of the invention are more fully described in 25 the following specification, set forth in the appended claims and illustrated in the accompanying drawings, wherein:

Figure 1 is an enlarged sectional view through two sections of a door showing the 30 lock in operation.

Fig. 2 is a similar view with the upper section of the door folded down.

Fig. 3 is a front elevation of the hinge.

Fig. 4 is a sectional view of Fig. 1.

When a hinge of this nature and as herein described is applied to the door of an automobile its lower member consists of a plate 10 secured to the inside of the door and made flush with the surface thereof and 40 having a knuckle 11 at its upper end. A lateral plate 12 is let into the upper horizontal surface of the door 13 and has a slot 14 near its outer end while a cavity 15 is cut in the door beneath the same. Both 45 of the plates 10 and 12 are rigidly secured to the door by screws or otherwise and the eye 11 is provided with a pintle 16 on which is pivoted the upper hinge member and which consists of the horizontal plate 17 50 and vertical plates 18 and 19 on the inside and outside respectively of the upper door section 20 and rigidly screwed and braced to the same so as to withstand the strain of the long leverage of any force put upon 55 the upper end of the said door section.

Swiveled in the plate 19 and loosely passing through the plate 18 is a screw 21 with a head 22 of any desired shape for manipulation and on the inner side of the door, while carried by the screw and adapted to 60 be moved in or out by the same is a yoke 23 retained in its vertical position by the walls of the recess 24 in the lower end of the door section 20.

In suitable bearings 25 on the plate 17 65 is pivoted a lever 26 whose lower end is a dog 27 adapted to enter the slot 14 which has an inclined front end 28 on which the face of the dog is adapted to play, and the upper end of the lever 26 has a pin 29 70 passing through it and playing in the jaws 30 on each side of the yoke 23. When the screw 21 is turned by means of the head 22 the yoke 23 is moved along the same and swings the lever 26 on its pivot 31, either to 75 lock the door sections 13 and 20 together, as shown in Fig. 1, or to release them as in Fig. 2 when one door section may be lowered.

When the sections occupy the latter position there are few or no obstructions to mar the finish of the car and little to indicate that the door is made of two pieces. The difficulty heretofore in the hinging and locking of the two door sections together 85 has been the liability of the parts to be broken by parties not familiar with the operation of the lock, or of parts of the device being lost or rattling on account of 90 looseness.

The present lock will secure the two sections rigidly and substantially, and the inclined wearing surface of the face of the dog with the edge of its slot may be relied upon to always assure a tight joint and one permitting 95 no rattling of the parts.

It is obvious that the parts may be otherwise arranged or modified without departing from the essential features above described or from the scope of the appended 100 claims.

What I claim is:

1. In a lock hinge, the combination with a rigid member having a socket, of a hinge member secured to the rigid member and having a perforated plate to fit around the socket, a second hinge member carrying a swinging member with a recess, a dog pivoted in the recess and having a hook adapted to extend into the socket and engage the 110

edge of the perforated plate when the swinging member is closed on the rigid member, and a screw operated outside of the swinging member and adapted to swing the dog to engage the perforated plate.

2. In a lock hinge, the combination with a hinge member comprising a vertical plate and a horizontal plate having a slot, of a second hinge member comprising two vertical plates united by a horizontal plate, a dog pivoted between the vertical plates and

adapted to play through the horizontal plate to enter the slot, a pin in the upper end of the dog, a screw carried by the vertical plates of the second member, and a yoke on 15 and actuated by the screw to straddle the pin on the dog and swing the latter.

Signed at New York, in the county of New York, and State of New York, this 15th day of February, A. D. 1917.

WILLIAM A. HENDERSON.

Copies of this patent may be obtained for five cents each, by addressing the "Commissioner of Patents, Washington, D. C."
